ALKYLATION AND ARALKYLATION OF
ORGANIC COMPOUNDS

David M. Jones, Richmond Heights, Mo., assignor
to Mallinckrodt Chemical Works, St. Louis,
Mo., a corporation of Missouri

No Drawing. Application March 11, 1941,
Serial No. 382,788

9 Claims. (Cl. 260—485)

This invention relates to agents and methods for introducing alkyl and aralkyl groups into organic compounds, and, more specifically, into mono-substituted malonic esters.

Among the several objects of the invention may be noted the provision of a new class of alkylating and aralkylating agents and a general process for carrying out alkylations and aralkylations of the types indicated which is characterized by its inexpensive and readily procurable raw materials, the ease with which it may be carried out, the simplicity of the process equipment, and the convenience of the operation. This latter factor is of particular advantage when alkylation or aralkylation of malonic esters produced by the processes described in the copending applications of Vernon H. Wallingford and August H. Homeyer, Serial No. 287,001, filed July 28, 1939, and Serial No. 374,254, filed January 13, 1941, is desired.

The invention accordingly comprises the steps and sequence of steps, and features of synthesis, analysis, or metathesis, which will be exemplified in the processes hereinafter described, and the scope of the application of which will be indicated in the claims.

The well-known methods for alkylating or aralkylating malonic esters generally involve, first, the formation of a metallo derivative of the appropriate malonic ester, and second, the reaction of this metallo derivative with an alkyl or aralkyl halide. In some cases, alkyl or aralkyl sulfates may be the preferred alkylating or aralkylating agents. These reactions are most frequently carried out in an alcoholic medium. These conventional procedures have the disadvantage that the alkyl and aralkyl halides are not commercially available in many cases, and in any event, are relatively expensive. The chlorides, though less expensive, are also less satisfactory than the more expensive bromides and iodides, so that these reagents do not readily lend themselves to economy in production. Of the dialkyl sulfates only dimethyl and diethyl sulfate are commercially available and, as a class, the sulfates are costly alkylating agents.

In contrast, the present invention, in many of its embodiments, provides inexpensive and readily accessible alkylating and aralkylating agents which can readily be made through a simple ester interchange.

Broadly speaking, the present invention comprises an entirely new class of alkylating and aralkylating agents and processes for the application of these agents. In the specific examples

below, alkylation and aralkylation of mono-substituted malonic esters are described. The reactions may be represented by the following equation:

wherein R is the alkyl, aryl or aralkyl substituent of the malonic ester, R' is an alkyl or aralkyl esterifying group, R'' is the alkyl or aralkyl group of the carbonate, and M is any suitable metal. Where alkyl radicals generally are referred to herein, aralkyl radicals are included.

The preparation of the metallo derivative of 15 the malonic ester may be carried out by any convenient means; advantageously by the procedure described by Vernon H. Wallingford and August H. Homeyer in their copending applications, Serial No. 287,000, filed July 28, 1939, and 20 Serial No. 383,164, filed March 13, 1941.

While the essence of the invention resides in the reaction between the metallo derivative and the dialkyl or diaralkyl carbonate, regardless of the manner in which the metallo compound is 25 formed, it is advantageous in some instances to take certain additional steps. For example, if the metallo compounds are prepared by the well-known reaction of a mono-substituted malonic ester with a metal alcoholate, according to the 30 equation:

it is in some cases advantageous to remove the 35 product alcohol, R''OH, before the alkylation or aralkylation step is begun. In other cases this product alcohol is without serious disadvantage.

Usually when the reaction is carried out by the use of a malonic ester, a metal alcoholate, and 40 a di-carbonate, the alkyl or aralkyl (alkoxy or aralkoxy) groups of the three reagents are identical, in order to prevent the formation of mixed products as a result of radical interchange. This is not always essential, however, for the reaction 45 will proceed satisfactorily when these groups do not correspond.

The use of the dialkyl or diaralkyl carbonate as the reaction medium, that is, carrying out the alkylation or aralkylation in a large excess of 50 the carbonate, is a distinct advantage in this process in many cases. This is due to both the cheapness of these materials and their manipulative convenience. They can be easily recovered and their presence inhibits side reactions. It has been found, however, that a part of the ex-

cess carbonate can be replaced by an inert solvent without disadvantage in some cases.

The mechanism of the reactions involved in the present invention has not yet been determined, but it probably closely parallels that of the well-known alkylations of metallo derivatives of malonic esters by dialkyl sulfates or alkyl halides.

The following examples illustrate certain specific embodiments of the present invention, but are intended to exemplify rather than limit.

EXAMPLE 1

Ethylation of diethyl ethylmalonate

A 1 liter, three-necked flask was arranged with a sealed stirrer and a five plate column. Anhydrous ethyl alcohol (250 ml.) was placed in the flask and sodium (11.5 g.) was reacted with it. Most of the excess alcohol was then distilled out at a final pressure of 20 mm. and bath temperature of 140° C. The residual, white solid cake was cooled and broken up and diethyl carbonate (400 ml.) was added. The remaining excess alcohol was then fractionated out at 150 mm. pressure. Then at a bath temperature of 80° C., diethyl ethylmalonate (94 g.) was added. The alcohol which formed (30 ml.) was distilled out at 150 mm. pressure and a bath temperature of 100° C. in one-half hour along with diethyl carbonate (40 ml.). Then, at atmospheric pressure and a bath temperature of 150–155° C., the mixture was refluxed five hours. The mixture was then cooled and treated with acetic acid (30 ml) and water. The oil was washed free of acid with water and dilute sodium carbonate solution. It was then dried with sodium sulfate and fractionated. After the diethyl carbonate was removed there was recovered 24% (23 g.) of the diethyl ethylmalonate, and there was obtained a yield of 54% (58 g.) of diethyl diethylmalonate. This is a 65% yield based on the diethyl ethylmalonate actually consumed. The diethyl diethylmalonate had a boiling point of 99–101° C. at 10 mm. and an *n* 20/D 1.4238–1.4240. This ester was identified by hydrolyzing it to obtain diethylmalonic acid which melted at 126–128° C. and showed no melting point depression in a mixed melting point with a known sample of diethylmalonic acid.

EXAMPLE 2

Ethylation of diethyl butylmalonate

In this case, the sodio-derivative of diethyl n-butylmalonate was prepared from ethyl caproate, by reaction with the diethyl carbonate, as described in the copending application of Wallingford and Homeyer, Serial No. 374,254, filed January 13, 1941, and then, without isolation, this compound was ethylated with the diethyl carbonate to produce diethyl ethylbutylmalonate.

A mixture was made of sodium ethylate (34 g.) and diethyl carbonate (400 ml.) as described in Example 1. At a bath temperature of 150–155° C., ethyl caproate (72 g.) was added during one hour. Ethyl alcohol (55 cc.) was formed and was fractionated out during three hours. The mixture was then refluxed for four hours. The mixture was then cooled and worked up as described in Example 1. There was recovered 33% (24 g.) of the ethyl caproate. There were obtained yields of 26% (28 g.) of diethyl butylmalonate and 34% (41 g.) of diethyl ethylbutylmalonate. This is a 50% yield of diethyl ethylbutyl malonate based on the ethyl caproate actu-

ally consumed. The diethyl ethylbutylmalonate had a boiling point of 122–124° C. at 12 mm. pressure, and an *n* 20/D 1.4280–1.4284. This ester was identified by hydrolyzing it to produce ethylbutylmalonic acid, which melted at 116–118° C.

EXAMPLE 3

Ethylation of diethyl isoamylmalonate

Similarly, the sodio derivative of diethyl isoamylmalonate was prepared from ethyl isoamylacetate, by reaction with diethyl carbonate, as described in the copending application of Wallingford and Homeyer, Serial No. 374,254, filed January 13, 1941, and then this compound was ethylated with diethyl carbonate to produce diethyl isoamylethylmalonate.

A mixture was made of sodium ethylate (16 g.) and diethyl carbonate (250 ml.) as described in Example 1. Then, at a bath temperature of 155–160° C., ethyl isoamylacetate (45 g.) was added. During three hours there was fractionated out 33 ml. of ethyl alcohol. Then the mixture was refluxed three hours at a bath temperature of 160–165° C. The mixture was then cooled and worked up as described in Example 1.

There was recovered 25% (11 g.) of the ethyl isoamylacetate. There was obtained a 25% (16 g.) yield of diethyl isoamylmalonate and there was obtained a 45% (32 g.) yield of diethyl ethylisoamylmalonate. This is a 60% yield of diethyl ethylisoamylmalonate based on the ethyl isoamylacetate actually consumed. The boiling point of the diethyl ethylisoamylmalonate was 135° C. at 16 mm. pressure and the *n* 20/D was 1.4290–1.4295. The ester was identified by hydrolyzing it to obtain ethylisoamylmalonic acid which melted at 120–121° C.

EXAMPLE 4

n-Butylation of di-n-butyl ethylmalonate

Sodium (4.6 g.) was reacted with n-butyl alcohol (100 ml.). Most of the excess butyl alcohol was then distilled out at a final pressure of 30 mm. and bath temperature of 180° C. The residual cake was cooled and broken up and di-n-butyl carbonate (250 ml.) was added. The remainder of the excess butyl alcohol was then fractionated out at 30 mm. and a bath temperature of 120–130° C. The mixture was then cooled to 100° C. and di-n-butyl ethylmalonate (49 g.) was added. During one hour, at a pressure of 30 mm. and bath temperature of 120–130° C., there was fractionated out 20 ml. of n-butyl alcohol. The mixture was then refluxed at a bath temperature of 150–160° C. for six hours. The mixture was then cooled and worked up as in Example 1.

There was recovered 38% (18.5 g.) of the di-n-butyl ethylmalonate and there was obtained a 42% (25.5 g.) yield of di-n-butyl ethylbutylmalonate. This is a 68% yield based on the di-n-butyl ethylmalonate actually consumed. The di-n-butyl ethylbutylmalonate had a boiling point of 117–119° C. at 1 mm. pressure and an *n* 26.5/D of 1.4324–1.4329. The ester was identified by hydrolyzing it to obtain ethylbutylmalonic acid, which melted at 116–117° C.

EXAMPLE 5

Isobutylation of di-isobutyl ethylmalonate

Sodium (4.6 g.) was reacted with isobutyl alcohol (100 ml.). Then the excess isobutyl alcohol was vacuum distilled out until a mush remained. Then di-isobutyl carbonate (200 ml.) and di-

isobutyl ethylmalonate (49 g.) were added. The mixture was then vacuum fractionated at 28 mm. pressure until the isobutyl alcohol was completely distilled out. The mixture was then refluxed at atmospheric pressure and a bath temperature of 165-170° C. for four hours. The mixture was then cooled and worked up as in Example 1. There was recovered 35% (17.5 g.) of the di-isobutyl ethylmalonate. There was obtained a 45% (26.5 g.) yield of di-isobutyl ethylisobutylmalonate. This is a 70% yield based on the di-isobutyl ethylmalonate actually consumed. The boiling point of the di-isobutyl ethylisobutylmalonate was 175° C. at 30 mm., and the *n* 26.5/D was 1.4320. The ester was identified by hydrolyzing it to obtain ethylisobutylmalonic acid, which melted at 109-110° C. The equivalent weight was found to be 94 (theory 96).

EXAMPLE 6

Isoamylation of di-isoamyl ethylmalonate

Potassium (7.6 g.) was reacted with isoamyl alcohol (100 ml.). Most of the excess isoamyl alcohol was vacuum distilled out. To the cooled mushy residue were added di-isoamyl carbonate (200 ml.) and di-isoamyl ethylmalonate (55 g.). Then the mixture was vacuum fractionated at 28 mm. until all of the isoamyl alcohol had been removed. The mixture was then stirred at atmospheric pressure and a bath temperature of 180-190° C. for four hours. The mixture was then cooled and worked up as described in Example 1.

There was obtained a 60% (42 g.) yield of di-isoamyl isoamylethylmalonate. The boiling point of the ester was 126-129° C. at 1 mm. pressure and the *n* 26/D was 1.4351-1.4359. The ester was identified by hydrolyzing it to obtain isoamylethylmalonic acid which melted at 120-121° C. and had an equivalent weight of 103 (theory 101).

EXAMPLE 7

Ethylation of diethyl n-octylmalonate

A mixture was made, as described in Example 1, of sodium ethylate (6.8 g.) and a small amount of ethyl alcohol. The mixture was cooled and diethyl carbonate (200 ml.) and diethyl octylmalonate (27 g.) were added. Then the mixture was vacuum fractionated at a bath temperature of 120° C. until the remaining original alcohol and that formed by reaction were entirely removed. Then the mixture was refluxed at a bath temperature of 155-160° C. for 4.5 hours. It was then cooled and worked up as described in Example 1. There was recovered 30% (9 g.) of diethyl octylmalonate and there was obtained a 33% (10 g.) yield of diethyl ethyloctylmalonate. This is a 50% yield based on the diethyl octylmalonate actually consumed. The boiling point of the diethyl ethyloctylmalonate was 122° C. at 1.5 mm. pressure and the *n* 26/D was 1.4334-1.4336. The ester was identified by hydrolyzing it to obtain ethyloctylmalonic acid, which melted at 82-83° C., and had an equivalent weight of 123 (theory 122).

EXAMPLE 8

Benzylation of dibenzyl ethylmalonate

A mixture was made of benzyl alcohol (25 ml.), sodium methylate (10.8 g.), dibenzyl carbonate (200 ml.) and dibenzyl ethylmalonate (62 g.) in a 500 cc., three-necked flask, arranged with a vacuum sealed stirrer and a fractionating col-

umn. The mixture was stirred and heated to a bath temperature of 190-200° C. at a pressure of 5 mm. During two hours 60 ml. of distillate was collected at a column head temperature of 75-80° C. The mixture was then refluxed four hours at the bath temperature of 190-200° C. The mixture was then cooled and worked up as described in Example 1. The dibenzyl carbonate was distilled off through a column at reduced pressure and then the residue was distilled from a Claisen flask. There was obtained a 53% (46 g.) yield of dibenzyl ethylbenzylmalonate of boiling point 245-247° C. at 2 mm. pressure and *n* 23.5/D of 1.5560. This ester was identified by hydrolyzing it to obtain ethylbenzylmalonic acid, which melted at 125-127° C. and had an equivalent weight of 112 (theory 110).

EXAMPLE 9

n-Butylation of di-n-butyl benzylmalonate

Potassium (5.5 g.) was reacted with n-butyl alcohol (100 ml.) and most of the excess n-butyl alcohol was vacuum distilled off. The solid residue was cooled and broken up and di-n-butyl benzylmalonate (43 g.) and di-n-butyl carbonate (200 ml.) were added to it. Then the mixture was vacuum fractionated at 28 mm. pressure and a bath temperature of 120° C. until all of the n-butyl alcohol was distilled out. Then the mixture was stirred at atmospheric pressure and a bath temperature of 180-190° C. for four hours. The mixture was cooled and worked up as described in Example 1. There was obtained an 80% (37 g.) yield of di-n-butyl butylbenzylmalonate of boiling point 172° C. at 3 mm. pressure and having *n* 25.5/D of 1.4770. The ester was identified by hydrolyzing it to obtain butylbenzylmalonic acid, which melted at 105-107° C. and had an equivalent weight of 127 (theory 125).

EXAMPLE 10

Alkylation of di-diethylcarbinyl ethylmalonate with di-diethylcarbinyl carbonate

Potassium (6.5 g.) was reacted with diethyl carbinol (125 ml.) and the excess carbinol was vacuum distilled out until a gummy residue was obtained.

Then di-diethylcarbinyl carbonate (200 ml.) and di-diethylcarbinyl ethylmalonate (45 g.) were added. The mixture was stirred and heated and the remaining original carbinol and that produced by the reaction were vacuum distilled out. The mixture was then stirred at atmospheric pressure and at a bath temperature of 180-190° C. for six hours. The mixture was cooled and worked up as usual. There was obtained a 35% (16 g.) yield of di-diethylcarbinyl diethylcarbinyl-ethylmalonate.

EXAMPLE 11

Ethylation of diethyl isopropylmalonate

The sodio derivative of diethyl isopropylmalonate was prepared from ethyl isovalerate, by reaction with diethyl carbonate, as described in the copending application of Wallingford and Homeyer, Serial No. 374,254, filed January 13, 1941, and then this compound was ethylated with the diethyl carbonate to produce diethyl ethyl-isopropylmalonate.

A mixture was made of sodium ethylate (27 g.) and diethyl carbonate (300 ml.) as described in Example 1. Then ethyl isovalerate (52 g.) was added. The mixture was stirred at atmospheric pressure and a bath temperature of 170-175° C. under a column, and low boiling material (27

ml.), mostly alcohol, was slowly fractionated out during twelve hours. The mixture was then cooled and worked up as described in Example 1. There was obtained a 10% (9 g.) yield of diethyl ethylisopropylmalonate, boiling point 112-114° C. at 18 mm. pressure. This ester was identified by hydrolyzing it to ethylisopropylmalonic acid, which melted at 132-134° C.

EXAMPLE 12

Ethylation of diethyl ethylmalonate

The magnesio derivative of diethyl ethylmalonate was prepared from magnesium turnings (12 g.), diethyl ethylmalonate (94 g.), anhydrous alcohol (60 ml.), and benzene (20 ml.) using carbon tetrachloride (1 ml.) as a catalyst, following well known procedures. After the reaction was complete, diethyl carbonate (400 ml.) was added and the alcohol, benzene, and part of the diethyl carbonate (170 cc. total distillate) was fractionated out under reduced pressure.

The resulting diethyl carbonate solution of diethyl magnesio-ethylmalonate was placed in a steel bomb and heated eight hours at a bath temperature of 220-225° C., at a pressure of 80 to 120 lbs. After cooling, the reaction mixture was poured into an equal volume of water, and made just acid with dilute hydrochloric acid. The oil was separated, washed with water, dried and fractionated. There was obtained a 22% recovery of diethyl ethylmalonate and a 50% yield of diethyl diethylmalonate, which represented about a 70% yield on the basis of the diethyl ethylmalonate actually consumed. The diethyl diethylmalonate boiled at 109-111° C. at 15 mm. pressure.

EXAMPLE 13

Butylation of di-n-butyl cetylmalonate

Sodium butylate solution prepared from n-butyl alcohol and 2.9 g. of sodium was vacuum evaporated until a thick mush remained and to this cooled residue was added di-n-butyl cetylmalonate (55 g.) and di-n-butyl carbonate (125 ml.). On warming and stirring the sodium butylate dissolved completely. Butyl alcohol was removed under vacuum, and then the mixture was refluxed at a bath temperature of 200-210° C. In half an hour the mixture had become a solid mass. This was heated five hours, cooled, decomposed with water, neutralized with acetic acid, the oil was separated, washed, dried and distilled. There was obtained a yield of 52 g. (83%) of di-n-butyl butylcetylmalonate boiling at 265-268° C at 4 mm. pressure and having n 20/D 1.4490 to 1.4502. The ester was converted to butylcetylmalonic acid by saponification with sodium hydroxide, followed by acidification, and the acid was purified by crystallization from petroleum ether. It melted at 97-98.5° C.

EXAMPLE 14

Ethylation of diethyl phenylmalonate

The sodio derivative of diethyl phenylmalonate was prepared from sodium ethylate (equivalent to 5.8 g. sodium) and diethyl phenylmalonate (59 g.) in diethyl carbonate (200 ml.) following the general procedure. The alcohol-free reaction mixture was placed in a steel bomb and heated at a bath temperature of 245-250° C. for seven hours, the pressure rising to 150 lbs. After cooling, the pressure was 30 lbs. and was due to carbon dioxide. This was vented and the reaction was heated for eight hours more, the final pressure being 145 lbs. After cooling, the reac-

tion mixture was made slightly acid with dilute acetic acid, the oily layer was separated and fractionated. A 30% yield (18 g.) of diethyl phenyl-ethylmalonate, identified by boiling point and refractive index was obtained. The melting point was found to be -9 to -7° C.

As indicated in the foregoing examples, the metallo compound can be prepared separately, and then alkylated or aralkylated in accordance with the present invention. Alternatively, the metallo compound can be prepared, for example, in accordance with the method described in the copending application of Wallingford and Homeyer, Serial No. 374,254, filed January 13, 1941, and the product without isolation may be alkylated or aralkylated in situ. The latter alternative of course obviates any recovery of the malonate or the metallo derivative of the malonate prior to alkylation.

Typical of the metallo derivatives which have been found suitable are the alkali metals, the alkaline earth metals, and aluminum.

It has been found that in most instances the alkylation or aralkylation should be carried out at a temperature of at least 100° C. Increasing the temperature seems to increase the rate of reaction. Temperatures substantially lower than 100° C. do not give an appreciable yield of alkylated or aralkylated compound in a reasonable time. For most purposes, a temperature substantially in excess of 100° C. is preferred.

In view of the above, it will be seen that the several objects of the invention are achieved and other advantageous results attained.

As many changes could be made in the above processes without departing from the scope of the invention, it is intended that all matter contained in the above description shall be interpreted as illustrative and not in a limiting sense.

What is claimed is:

1. The method of alkylating a metallo derivative of a mono-substituted malonic ester selected from the group consisting of alkali metal, alkaline earth metal and aluminum derivatives which comprises reacting the derivative with a dialkyl carbonate.

2. The method of alkylating a malonic ester of the type $R \cdot C(M)(CO_2R')_2$, in which R is selected from alkyl, aryl and aralkyl radicals, R' is selected from alkyl and aralkyl radicals, and M is an alkali metal, which comprises reacting the ester with a dialkyl carbonate.

3. The method of alkylating a malonic ester of the type $R \cdot C(M)(CO_2R')_2$, in which R is an organic group attached by an aliphatic linkage, R' is selected from alkyl and aralkyl radicals, and M is a metal selected from the group consisting of alkali metals, alkaline earth metals and aluminum, which comprises reacting the ester with a dialkyl carbonate.

4. The method of alkylating a malonic ester of the type $R \cdot C(M)(CO_2R')_2$, in which R is selected from alkyl, aryl and aralkyl radicals, R' is selected from alkyl and aralkyl radicals, and M is selected from the group consisting of alkali metals, alkaline earth metals and aluminum, which comprises reacting the ester with a dialkyl carbonate.

5. The method of alkylating a malonic ester of the type $R \cdot C(M)(CO_2R')_2$, in which R is an organic group attached by an aliphatic linkage, R' is selected from alkyl and aralkyl radicals, and M is an alkali metal, which comprises reacting the ester with a dialkyl carbonate.

6. The method which comprises reacting a

substituted acetic acid ester with an alkali metal alcoholate and a dialkyl carbonate to metallate and carbalkoxylate the ester, and alkylating the metallo product with a dialkyl carbonate.

7. The method which comprises reacting a substituted malonic acid ester with an alkali metal alcoholate and a dialkyl carbonate.

8. The method of alkylating a malonic ester of the type $R \cdot C(M)(CO_2R')_2$, in which R is selected from alkyl, aryl and aralkyl radicals, R' is selected from alkyl and aralkyl radicals, and M is

an alkali metal, which comprises reacting the ester with a dialkyl carbonate and distilling the product alcohol from the reaction mixture.

9. The method of alkylating a malonic ester of the type $R \cdot C(M)(CO_2R')_2$, in which R is an organic group attached by an aliphatic linkage, R' is selected from alkyl and aralkyl radicals, and M is an alkaline earth metal, which comprises reacting the ester with a dialkyl carbonate.

DAVID M. JONES.
